(57) CLAIM

The ornamental design for a sport towel, as shown and described.

DESCRIPTION

FIG. 1 is a front view of a sports towel.

FIG. 2 is a back view of the sports towel shown in FIG. 1.

FIG. 3 is a left side view of the sports towel shown in FIG. 1.

FIG. 4 is a right side view of the sports towel shown in FIG. 1.

FIG. 5 is a top view of the sports towel shown in FIG. 1.

FIG. 6 is a bottom view of the sports towel shown in FIG. 1; and,

FIG. 7 is a perspective drawing of the sports towel of FIG. 1 showing the front view.

In the drawings, the broken lines represent stitching.
